SHARPENING MECHANISM

Louis V. Aronson, Newark, N. J., assignor to Art Metal Works, Inc., a corporation of New Jersey

Application June 25, 1932, Serial No. 619,204

6 Claims. (Cl. 51—96)

(Cl. 51—96)

This invention relates to a sharpening mechanism for sharpening razor blades and the like.

Among the objects of this invention is the provision of an improved sharpening mechanism including a razor blade supporting means and a sharpening device so related and mounted as to facilitate the conditioning of the mechanism for honing or grinding each face of both edges of a double-edged safety razor blade.

10 A more specific object of the invention is to provide means for supporting a sharpening roller movably so as to permit the same to be moved into and out of cooperative relation with both faces of the edges of the razor blade. Certain of 15 the improvements are applicable to single-edged razor blades, while other features are specially useful in connection with sharpening double-edged safety razor blades.

20 Other objects of the invention will appear from the following description taken in connection with the drawing, in which

Fig. 1 is a top plan view of the sharpening mechanism;

Fig. 2 is a section taken substantially on the line 2—2 of Fig. 1;

Fig. 3 is a longitudinal diametral section taken substantially on the line 3—3 of Fig. 2;

Fig. 4 is a section on the line 4—4 of Fig. 1;
Fig. 5 is a section substantially similar to Fig.
30 2 but with the parts shown in another position;

Fig. 6 is a section taken on the line 6—6 of Fig. 1.

Fig. 1.
The supporting frame comprises a reel including disk-like end members 7 and 8 and spacing rods 9 and 10, said end members and spacing rods being secured together by screws 11. The spacing rods are preferably located in a dia-

40 metral plane for purposes later set forth.

45 The end member 7 is preferably provided with a hub 12 constituting a bearing for a short shaft 13 on which an operating crank handle 14 is non-rotatably mounted. The handle may be secured on the shaft by a screw bolt 15. The inner end of the short shaft 13 may be provided with an enlarged portion 16 on which is non-rotatably mounted a gear 17 which will be referred to later. The inner end of the short shaft is provided with a cylindrical recess constituting a bearing for the reduced end 18 of a razor blade supporting shaft 19, the other end of which may be provided with a conical recess receiving the conical end 20 of a screw bolt 21 threadedly mounted in the end member 8 and adapted to be locked in adjusted position by a lock nut 22.

50

55

The shaft 19 may be provided with a reduced portion 23 on which is secured a disk 24 bearing against a friction disk 25 seated loosely in a recess in the side of the gear 17.

60. As will be obvious, when the operating han-

die 14 is rotated in either direction to rotate the gear 17, the shaft 19 which supports the razor blade 26 will be moved in the same direction by frictional engagement between the friction disk 25 and the disk 24 and the surface of the recess in the gear 17. The amount of friction between these parts may be increased or diminished by adjusting the screw bolt 21.

For the purpose of securing the razor blade 26 in position on the shaft 19 the central portion of the shaft is preferably made semi-cylindrically in form, as indicated at 27, to provide a seat for a razor blade and to receive a semi-cylindrical clamping member 32 apertured at 28 and 29 to receive aligning pins 30 and 31 on 15 the seat 27. The clamping member 32 is preferably secured to the shaft 19 by means of a screw bolt 33 which preferably has a swivel connection with the clamping member 32.

The sharpening device employed may be in the form of a roller 35 non-rotatably mounted on a shaft 36, the ends of which are reduced and supported in bearings on arms 37 and 38 secured to a sleeve 39 freely mounted on the spacing rod 9. The end members 7 and 8 are preferably provided with arcuate slots 40 and 41 in which the shaft bearings on the arms 37 and 38 operate. Secured to the sleeve 39 is an arm 42 provided with a slot 43 in which operates a pin 44 mounted eccentrically on a disk 45 fixed on a shaft extending through the end member 7 and carrying at its outer end a short operating lever 46. By operating the lever 46, the sharpening roller may be moved into the positions indicated in the drawing. In Fig. 5, the sharpening roller is in position to permit rotation of the razor blade while in the remaining figures it is in position to sharpen the razor blade.

Cooperating with the gear 17 is a small gear 48 mounted on a stud supported in the end member 7 and with which is adapted to mesh a gear 49 non-rotatably mounted on the shaft 36 which supports the sharpening roller 35. When the lever 46 is in the position shown in Figs. 2 and 6 the gear 49 is in mesh with the gear 48 whereby upon rotation of the operating handle 14 in either direction the sharpening roller will be rotated in the same direction as the handle. The frictional driving connection between the short shaft 13 and the shaft 19 which supports the razor blade will cause the razor blade to rotate with the handle to move one face of one edge of the razor blade into cooperative relation with the roller. By moving the crank 14 first in one direction and then in the other direction the faces of the edges on the same side of the razor blade may be honed or ground. If it is desired to hone or grind the opposite faces it will only be necessary to move the lever 46 into the position shown in Fig. 5. This moves the sharpening roller radially with

respect to the razor blade supporting shaft a sufficient distance to permit the razor blade to be turned so that the opposite faces of the edges of the blade will be in position to be honed or ground after the roller is again moved into the position shown in Figs. 2 and 6.

For conveniently holding the sharpening mechanism in the left hand as the crank is being operated by the right hand, I provide a holding handle 50 which is provided with a slot 10 removably engaging the spacing rod 10 and which is also provided at its inner end with a screw threaded pin projecting through a hole in the end member 7 and secured thereto by a knurled nut 51. The handle is preferably made detachable for convenience in packing the device in a case.

The pressure between the razor blade and sharpening roller may be regulated by adjusting the screw bolt 21. The parts are constructed for easy assembling and the handle 50 may be quickly detached if desired. When it is desired to secure the razor blade on the shaft or to remove it, the mechanism may be laid on a table or shelf with the holding handle 50 and the operating crank handle 14 resting on the table and the shaft 19 may then be moved into a position in which the spacing rods 9 and 10 will act as a guard for the edges of the razor blade. After one of the faces of both edges of the razor blade has been honed or ground by turning the crank handle 14 first in one direction and then in the opposite direction, the mechanism may be conditioned to hone or grind the opposite faces by moving the sharpening roller into the position shown in Fig. 5, then rotating the razor blade from the solid line position to the broken line position, Fig. 6, and then moving the sharpening roller into the position shown in Fig. 6. The opposite faces, as indicated by the broken lines in Fig. 6, may now be honed or ground by operating the crank handle 14 as before.

While this invention has been described with particularity as to the single embodiment disclosed, it is obvious that other embodiments may be suggested to those skilled in this art after understanding this invention, and it is to be understood that words of description imported into the claims are not to be considered as limitations except as necessitated by the prior art.

What I claim is:

1. In a sharpening mechanism, the combination of a frame, a razor blade supporting shaft mounted for rotation in said frame, a rotatable sharpening device, means for rotating said sharpening device in either direction, a frictional drive between said first mentioned means and said razor blade supporting shaft for moving said razor blade into engagement with said sharpening device, and means movably supporting said device on said frame for movement into contact with a razor blade supported on said shaft and for movement away from said shaft to permit the razor blade to be moved on the opposite side of said sharpening device for the purpose of permitting both faces of an edge of the blade to be honed or ground.

2. In a sharpening mechanism, the combination of a frame, a razor blade supporting shaft mounted for rotation in said frame, a rotatable sharpening device, means for rotating said sharpening device in either direction, a frictional drive between said first mentioned means and said razor blade supporting shaft for moving said razor blade into engagement with said sharpening device, and means movably supporting said

device on said frame for movement into contact with a razor blade supported on said shaft and for movement away from said shaft to permit the razor blade to be moved on the opposite side of said rotatable sharpening device for the purpose of permitting both faces of an edge of the blade to be honed or ground.

3. In a sharpening mechanism, the combination of a frame, a razor blade supporting shaft, a rotatable sharpening roller, a driving means for rotating said roller, a frictional connection between said driving means and said shaft for causing a razor blade on said shaft to move into contact with said roller upon movement of said driving means, and movable means for supporting said roller for movement into cooperative position with a blade on said shaft and for movement away from said shaft beyond the edge of said blade whereby the opposite face of an edge of the blade may be presented to said roller by first moving said blade to the opposite side of said roller and then moving the roller into cooperative relation with said blade.

4. In a sharpening mechanism, the combination of a frame including end members and spacing members, a sharpening roller, bearing elements for said sharpening roller pivotally mounted on one of said spacing members, a razor blade supporting shaft supported in said end members, means for rotating said roller and for frictionally rotating said shaft to move the blade carried by said shaft into contact with said roller, and means for moving said roller away from said blade for permitting said shaft to be rotated to present the opposite face of the edge of the razor blade in position to cooperate with said roller after said roller has been moved into its normal position with respect to said shaft.

5. In a sharpening mechanism, the combination of a frame including end members, a razor blade supporting means, a rotatable sharpening roller, a pair of pivotally mounted arms for supporting said roller, a slotted operating arm connected to said pivotally mounted arms, a pin cooperating with said slot, and a lever mounted on said end member for moving said pin transversely with respect to said operating arm for moving said roller into and out of cooperative relation with respect to a razor blade carried by said razor blade supporting means.

6. In a sharpening mechanism, the combination of a frame, a rotatable sharpening roller mounted in said frame, a razor blade supporting shaft mounted in said frame and having provision for supporting a double-edged razor blade, common driving means for rotating said sharpening roller and shaft in the same direction to move one face of one edge of said razor blade into engagement with one side of said roller as said roller is being rotated, a frictional drive between said shaft and common driving means whereby said face of said edge of the blade may be held in contact with said side of the roller as the roller is rotated, said roller and shaft being rotatable in the opposite direction to bring the face of the other edge of the blade, located on the same side of the blade, into cooperating relation with the other side of the roller, and means for moving said roller away from said shaft whereby a blade on said shaft may be rotated by said driving means to present its other faces to said roller upon operation of said driving means after said roller has been returned into functioning position.
